CURL FOR WIGS

Jules Fabre, Gaillac-sur-Tarn, France

Application June 23, 1953, Serial No. 363,561

2 Claims. (Cl. 132—55)

Scrolls, locks and ringlets can be regarded as belonging to the oldest fashions in the art of hair-dressing. They have been made of natural hair both in scalp and periwig work.

As a consequence of the fact that no particular expedient or contrivance was availed of to keep them in the curled shape, they would early loosen and repeatedly require the hair-dresser's care although a lock is never as long as any hair therein.

Now that hair-imitating synthetic fibres have been developed, periwig can be manufactured from such materials, the hair-dressing techniques remaining the same as with natural hair-dressing except higher heating temperatures are used.

Over natural hairs synthetic fibres afford the advantage that much longer ringlets can be obtained.

Heretofore, where such synthetic filaments were used, a maximum strength or fixedness was conferred upon the three aforementioned hair-dressing fashions with the aid of stitches.

The method according to the present invention, which affords many advantages over the one including stitches and the purpose of which is to obtain coils made of rayon or like synthetic fibres and suitable as scrolls, locks or ringlets in hair-dressing are remarkable notably thereby that:

Firstly, a strand is made which includes one or several threads;

A core rod of suitable diameter and length is mounted on a frame around which the strand is to be wound;

A tape is suitably stretched or wound around said core rod which is coated with an adhesive on its outside;

Contingently, one or thin yet strong threads made of a suitable material are stretched along the core rod;

The strand is wound mechanically around the core rod by spinning the same about its axis while traversing the intake end of the strand along the rod.

A single-thread strand is obtained by winding up the fibre as one single thread around a reel. By winding off any desired number of threads from as many reels a strand can be obtained having the desired thickness suited to the size of the periwig, the thickness of the individual threads being likewise optional.

There is also shown a core rod around and along which the strand is exchangeable and mounted preferably horizontal. The core rod may be made of glass, metal, plastic or like suitable material and its section may be circular although in particular instances it may well be oval. Of course, the diameter of the core rod depends upon that of the coil to be obtained; however, practically, its length should not exceed 3 meters. The rod may be solid or hollow and include one single or several sections. It may be heated in any suitable manner.

In coiling the strand around the core rod a strand guide is used which normally is traversed in continuous motion, whereby the thread can be coiled in close turns on the

2

rod. However, with certain fibres, a reciprocated strand guide may also be utilized.

A particular embodiment of my invention will be described more specifically hereinafter, reference being had to the appended drawing in which:

Figure 1 is a perspective view of a machine suitable for the performance of my invention.

Figure 2 is an enlarged sectional view of the core rod.

Figure 3 is an enlarged perspective view of a ringlet section.

Mounted on the bed 1 of the machine between a head-stock 3 and a tail-stock 4, movable lengthwise of the bed on guide rails 5, is a core rod 2 which is spun by means of a mechanism enclosed in the casing 6 and which also spins the lead screw 7. A thread-guide composed of a pair of idle rolls 8, 9, of which the one is fixed while the other is pressed towards the same by a spring 10 is also shown. This thread guide is mounted on a carriage 11 guided by said rails 5 and traversed with the aid of a nut 12 cooperating with the lead screw 7; the filaments coming from the reel 13 run through and are spread by the thread guide, after which they are wound up in uniformly spaced turns around the core rod 2.

Before the threads 14 are coiled around the core rod 25 a tape 15 is stretched lengthwise of the same with its adhesive-coated side 16 turned outwards, contingently together with a number of threads as shown at 17 in Fig. 2.

Preferably, the core rod is cut with a longitudinal slit 18 the purpose of which will be explained later on. The mechanical laying of the threads as tightly-coiled turns leads to the obtainment of hair-dressing attires in which lie parallel to one another the same as does the thread on a bobbin, which result has never been achieved in the art of hair-dressing.

35 My method can be carried into effect as follows: Prior to the mechanical feeding of the strand to the core rod 2—which can be started as soon as the latter is set and everything ready—a tape 15 is laid and tightly stretched along a generatrix or a spiral line of the rod 40 with its adhesive-coated side turned outwards. Of course, the width of the tape must be such that the fibre strand can easily be fixed thereon.

Preferably, the inside of the tape is made of a slippery, e. g. cellulosic material in order to facilitate the subsequent stripping.

Moreover, a number of thin (e. g. 0.5 to 1 mm. gauge) plastic threads 17 may be stretched along the core rod. Similar to the tape, said threads should be temporarily glued to the ends of the core rod.

50 Once the strand payed off by the reel and taken up by the rod is thus fixed on the tape or strip, a half-finished article is obtained.

Usually, and depending on the character of the fibres, a curl-setting treatment must be performed, preparatory 55 to which the articles should be softened for a variable time in cold, warm or hot water to which soapy products may or may not be added, the said articles thereafter being dried.

Next, the coil obtained must be stripped off, a procedure which is facilitated considerably by the provision of the aforementioned threads 17 which can easily be pulled out one after the other.

Care must be taken not to allow the cellulosic material to stick to the core rod, least of all where same is made 65 of glass.

The coil thus obtained will come off as a nicely uniform ringlet of just the same length as the core rod as shown in Fig. 3.

70 Since the coil is firmly held all over its length by the adhesive tape 15, it can be fractioned anywhere and will none the more uncurl. It may be applied directly to the

pasteboard or fabric backing of a doll's scalp. Effectively, since the adhesive-coated side of the tape 15 is turned downwards the outside, it is only necessary to gently press the tape onto the backing to cause the excess adhesive on the former to ooze into the latter. No stitching work is necessary, which involves a considerable saving in labour costs, in addition to which the scroll can be arranged much more easily and accurately on the backing.

The advantages to be derived from the application of my invention may be summarized as follows:

1. Scrolls, locks and ringlets are obtained in the "best-finished" state.
2. The products may be obtained in any desired shapes and lengths, which opens the way to every kind of quickly-performed hair-dressing work.
3. The ringlet can be cut into sections without deteriorating the same.
4. Indeformable ringlets are obtained which can more readily be affixed to scalps of every kind.
5. In the performance of the method according to my invention it is only necessary to carefully apply it as well-combed spirals onto the core rod.

If this work were performed by hand it would not be possible to coil the fibres uniformly around the core rod however skilled the operator might be, and thicker sections would always be found in the work.

Coils obtained according to this new method are quite suitable in the manufacture of periwig including scrolls, locks or ringlets to be worn by persons or even animals, or set on such articles of manufacture as manikins, statuettes, religious figures, busts, mascots, dolls, puppets, and so on.

The tubular coil thus obtained on the core rod may thereafter be cut open over its whole length, preferably along a generatrix close to the one edge of the supporting strip.

Preferably, in order to facilitate the slitting of the tubular coil, a longitudinal groove 18 of suitable width and depth is provided in the core rod as a guide for a cutting tool which preferably is actuated mechanically; of course,

the tubular coil may also be cut open in any suitable way after it has been taken away.

By thus cutting the tubular coil along a generatrix of the same a fringe is obtained in which the hairs are kept substantially parallel to one another and, disregarding the curvature resulting from the coiling process, either at right angles or obliquely to the edge of the tape depending on whether the latter was laid straight or along a helical line on the core rod.

10 In addition to the scrolls, locks and ringlets which can be obtained by leaving the coil uncut, various other fashions may be obtained after the same has been cut open as explained, notably particular waving effects, carnival or stage periwigs, false beards and mustaches, dolls' headresses, and so on.

15 It will be appreciated that simply by laying a number of hair-lined tape lengths in overlapping rows on a backing same can readily be covered with a fleece of ready-curved hairs lending themselves to a great many waving effects.

20 It will also be appreciated that the hair thus applied in layers on a backing may subsequently be "ironed out" by any method well known in the art.

What I claim is:

- 25 1. A curl for hair-dressing purposes which consists of a synthetic fibre coil the turns of which are held in close relation to and parallel with one another, and a tape having an adhesive coated surface, said tape being inside said coil, said surface being cemented to said turns to hold same in place.
- 30 2. The curl of claim 1 wherein the coil is cut along a line generally parallel to the axis of said coil.
